UNITED STATES PATENT OFFICE.

OTTO H. MOHR, OF CHICAGO, ILLINOIS.

DESIGN FOR A STATIONARY LIGHTING-FIXTURE.

50,027.

Specification for Design.

Patented Dec. 12, 1916.

Application filed September 28, 1916. Serial No. 122,763. Term of patent 14 years.

To all whom it may concern:

Be it known that I, OTTO H. MOHR, a citizen of the United States, residing at Chicago, in the county of Cook and State of Illinois, have invented a new, original, and ornamental Design for a Stationary Lighting-Fixture, of which the following is a specification, reference being had to the ac-

companying drawing, forming part thereof.

The figure is a perspective view of a stationary lighting fixture, showing my new design.

I claim:

The ornamental design for a stationary lighting fixture, as shown.

OTTO H. MOHR.
